UNITED STATES PATENT OFFICE

2,386,370

HAND OR POINTER REMOVER

Vernon V. Vaughan, Norfolk, Va.

Application January 6, 1944, Serial No. 517,253

3 Claims. (Cl. 81—6)

This invention relates to a pulling tool for use by clock makers and others doing similar work upon instruments having hands or pointers and it is one object of the invention to provide a tool by means of which the hands of a clock or watch or the pointer of a gauge or similar instrument may be removed from the shaft carrying the same without bending the hands or the pointer.

Another object of the invention is to provide a puller of such formation that it may be held in a person's hand and actuated by squeezing pressure applied to a handle and a lever constituting elements of the puller.

Another object of the invention is to provide a tool of this character wherein jaws are pivoted to the lower end of a plunger and moved towards a gripping position by action of a collet about the lower end of a barrel in which the plunger is mounted when the plunger is shifted upwardly through the barrel by pressure applied to a plunger-operating lever.

Another object of the invention is to provide a pulling tool wherein the plunger is yieldably held against upward movement by a spring surrounding the plunger within the barrel housing the plunger and the jaws urged towards a releasing or inoperative position by a spring in the lower portion of the plunger.

Another object of the invention is to so form the barrel and the collets that a set of collets of various sizes may be provided and selectively applied to the lower end of the barrel as needed.

Another object of the invention is to provide a puller which is simple in construction, easy to operate and capable of being quickly taken apart for cleaning or repairs and reassembled.

The invention is illustrated in the accompanying drawing wherein:

Figure 1 is a side elevation of the improved puller.

Figure 2 is a top view thereof.

Figure 3 is a sectional view taken along line 3—3 of Figure 2.

Figure 4 is a sectional view taken at right angles to Figure 3 along line 4—4 of Figure 1.

Figure 5 is a top plan view of a collet or sleeve constituting an element of the puller.

Figure 6 is a sectional view taken along line 6—6 of Figure 5.

Figure 7 is a sectional view taken at right angles to Figure 6 along the line 7—7 of Figure 5.

This improved pulling tool is for use by clock makers, instrument repair men and others whose work requires removal of hands or pointers from shafts upon which they are mounted and has a

barrel 1 formed of strong metal and formed with a bore 2 which is of even diameter for the major portion of its length but has its upper end portion 3 of reduced diameter to form an annular shoulder 4 and an inwardly thickened upper portion for the barrel diametrically across which a slot 5 is formed in the upper end of the barrel. The lower portion 6 of the barrel is externally thickened and this thickened lower portion defines a circumferentially extending shoulder 7 spaced upwardly from the lower end of the barrel. A lug 8 extends radially from the barrel above the thickened portion 6 thereof and is of such diameter that it will fit tightly into the hollow neck 9 of a handle 10. Therefore, the handle will be firmly held to the barrel but may be detached therefrom when so desired.

A piston or plunger 11 is slidably received in the barrel and has its lower portion of increased diameter to form a head 12 which is formed across its lower end portion with a diametrically extending slot 13 and bored longitudinally to form a socket 14. The plunger is of greater length than the barrel and its upper portion is formed with a slot 15 having a diagonally extending lower end 16. A cross-bar 17 extends across the upper end of the slot 15 at the front thereof, and referring to Figure 3 it will be seen that this cross-bar has a transversely rounded lower edge face 18. A spring 19 yieldably resists upward movement of the plunger and is coiled about the plunger within the barrel with its upper end bearing against the shoulder 4 and its lower end resting upon the shoulder 20 at the upper end of the head 12 of the plunger.

In order to engage and grasp the hands of a clock or the pointer of a gauge or similar instrument there has been provided jaws 21 which fit within the slot 13 and are pivotally mounted by a pin 22 which passes through the jaws and has its end portions engaged in openings formed in the plunger near the lower end thereof. These jaws have wide feet or hooks 23 at their lower ends so that when the jaws are swung towards each other they may have good engagement under the hands or pointer and cause the hands or pointer to be easily lifted off the shaft carrying the same. Upper end portions of the jaws are tapered to form cam portions 24 between which is disposed a pin 25 which is engaged with the lower end of spring 26 housed in the socket 14. This spring exerts downward pressure upon the pin and the cam members 24 will thus be urged away from each other and the jaws swung to opened or inoperative position. Since ends of

the pin 22 are exposed through slots 21 formed in the lower end portion of the barrel, the pin may be removed to release the jaws and other jaws substituted.

Movement of the jaws towards each other is effected by upward movement of the plunger and in order to shift the plunger upwardly there has been provided a lever 28 which is disposed over the handle 10 and has its front end downwardly thickened to form a foot 29 formed with a straight lower edge. The lower edge portion of the foot fits snugly in the slot 15 at the upper end of the plunger and also in the slot 5 at the upper end of the barrel. The foot tapers towards its front end and near its front end is formed a substantially circular opening or recess 30 having a flaring throat 31 through which the cross-bar 18 is passed into the recess 30. Since the recess is circular and the under surface of the cross-bar is curved transversely, the cross-bar may have sliding movement circumferentially of the recess without scratching or binding when pressure is applied to the lever by the thumb of a hand grasping the handle 10 and the lever. As the lever is forced towards the handle by pressure the plunger is shifted upwardly and by tilting the lever until the diagonally extending face 32 of the shoe rests upon the upper end of the barrel, the plunger will be held in a raised position.

During upward movement of the plunger a sleeve or collet 33 carried by the lower end portion of the barrel exerts cam action upon the jaws to force them towards each other to an operative or gripping position. This collet fits about the barrel with its upper end bearing against shoulder 7 and the upper portion of the collet is formed with slits 34 so that it may be expanded slightly as it is applied and have frictional grip about the barrel and be firmly but removably held in place. The lower portion of the collet is formed with slots 35 at right angles to the slits 34 and below the slits the collet is internally thickened to form shoulders 36 engaging the lower edge of the barrel and also providing the collet with a lower portion of predetermined internal diameter. By so forming the collet its cam action upon the jaws may be controlled and the jaws caused to be moved towards a closed position a desired extent when the plunger is shifted upwardly. By removing a collet in use and substituting another having a lower portion of different internal diameter the extent to which the jaws close may be varied. When the lever is released the spring 19 shifts the plunger downwardly and the spring 26 causes the jaws to be swung to opened position.

Having thus described the invention, what is claimed is:

1. A hand-removing tool comprising a barrel, a plunger slidably longitudinally through the barrel, an enlarged head on the lower end of the plunger, a cross-bar at the top end of the plunger, a spring in the barrel coiled about the plunger and bearing against the barrel and head of the plunger for urging the plunger downwardly, said plunger having its lower end portion formed with a transverse slot and with a longitudinal socket, jaws pivotally mounted in the lower end of said plunger and projecting downwardly from the plunger the upper portions of the jaws being en-

larged to form camming elements, a spring in the socket disposed between the enlarged camming upper portions of the jaws and urging the jaws away from each other to opened position, a sleeve fitting about the lower portion of the barrel and thickened at its lower end to form shoulders engaging the jaws to force the jaws towards each other to closed position when the plunger is shifted upwardly, said sleeve being removable from the barrel and having its upper portion slit longitudinally to provide for frictional gripping engagement with the barrel, a handle extending from said barrel, and a lever having a foot at its front end formed with a circular recess leading from its upper edge and through which the cross-bar passes to operatively connect the lever with the plunger.

2. A hand-removing tool comprising a barrel having an outstanding annular shoulder about its lower portion, a sleeve removably fitting about the lower portion of the barrel with its upper end abutting said shoulder, the lower portion of the sleeve being internally thickened to provide a predetermined internal diameter, a plunger 25 slidable longitudinally in said barrel and having its lower portion formed with a transverse slot and a longitudinal socket extending upwardly from the slot, a spring in said socket, jaws pivotally mounted in said slot and extending downwardly out of the sleeve, said jaws having diverging thickened upper portions forming camming surfaces, a pin at the lower end of said spring disposed between the camming surfaces of the diverging upper portions of the jaws and urging the jaws apart by pressure of the spring, said sleeve having its lower edge engaging outer side edges of the jaws for forcing the jaws towards each other to a gripping position when the plunger is shifted upwardly, a spring about the plunger for urging the plunger downwardly, and a lever passing through an opening in the plunger above the barrel and engaging the same for moving the plunger upwardly within the barrel.

3. A hand-removing tool comprising a barrel, a sleeve about the lower end of the barrel said barrel having a relatively thick top portion with a transverse slot, a plunger slidably longitudinally in said barrel, jaws pivoted to said plunger and extending downwardly from the plunger and out of the sleeve, cam portions at upper ends of said jaws, a spring carried by said plunger and acting upon the cam portions for urging the jaws away from each other to opened position, said sleeve engaging the jaws and forcing the jaws towards each other when the plunger is shifted upwardly, the upper end portion of the plunger being formed with a diametrically disposed longitudinally-extending slot above the barrel and forming a cross-bar across the upper end of the plunger, a handle carried by and extending transversely from said barrel, and a lever for shifting the plunger upwardly having a tapered front portion resting upon the upper end of the barrel and passing through the slot of the plunger below the cross-bar and formed with a substantially circular recess through which the cross-bar passes, said recess having a flaring mouth leading from the upper edge of the lever for introduction of the cross-bar into the recess.
